DINNER PLATE OR SIMILAR ARTICLE

Edward M. Otis, Syracuse, N. Y., assignor to Onondaga Pottery Company, Syracuse, N. Y., a corporation of
New York

Application January 9, 1957, Serial No. 44,458

Term of patent 14 years

(Cl. D44—15)

The figure is a plan view of a plate of conventional configuration showing my new design.

I claim:

The ornamental design for a dinner plate or similar article, as shown and described.
